RING

Louis Solomon, 3600 N. Talman Ave., Chicago, Ill.

Filed Feb. 21, 1964, Ser. No. 78,716

Term of patent 14 years

(Cl. D45—10)

FIG. 1 is a top plan view of a ring embodying my new design;

FIG. 2 is a front elevational view;

FIG. 3 is a rear elevational view;

FIG. 4 is a right side view; and

FIG. 5 is a left side view of the same.

FIG. 6 is a sectional view taken on line 6—6 of FIG. 2.

The dominant features of the design reside in the full line portions of the drawings, variable letters or initials being shown in broken lines superposed over the opening in the bezel, while variable insignia are positioned in the contrasting side panels, all as shown.

I claim:

The ornamental design for a ring, substantially as shown and described.
